Primary Examiner—Robin V. Taylor(74) *Attorney, Agent, or Firm*—Knobbe, Martens, Olson & Bear, LLP(57) **CLAIM**

The ornamental design for a fluid dispensing apparatus, as shown and described.

DESCRIPTION

FIG. 1 is a front perspective view of the fluid dispensing apparatus of the present invention;

FIG. 2 is a left-side elevational view thereof;

FIG. 3 is a front elevational view thereof;

FIG. 4 is a right-side elevational view thereof;

FIG. 5 is a rear elevational view thereof;

FIG. 6 is a top plan view thereof; and,

FIG. 7 is a bottom plan view thereof.

The broken line showing is for illustrative purposes only and forms no part of the claimed design.
